FOLDABLE TRAVERSING SCREEN

James Hirashiki, Los Angeles, Calif., assignor to Jaylis Industries, Inc., Los Angeles, Calif., a corporation of California

Filed Nov. 21, 1963, Ser. No. 77,531

Term of patent 14 years

(Cl. D54—2)

FIGURE 1 is a perspective view of a foldable traversing screen showing my new design.

FIGURE 2 is a perspective view on a larger scale of one of the repeating individual blocks from which said foldable traversing screen is assembled.

FIGURE 3 is a perspective view on a larger scale of a modification of the repeating individual blocks of FIGURE 2.

The rear of the screen not shown is substantially the same as the front shown except in reverse.

I claim:

The ornamental design for a foldable traversing screen, substantially as shown and described.
